UNITED STATES PATENT OFFICE.

EMIL STRANSKY, OF CANAL DOVER, OHIO.

STAND FOR ELECTRIC IRONS.

1,331,400.

Specification of Letters Patent. Patented Feb. 17, 1920.

Application filed March 18, 1919. Serial No. 283,297.

To all whom it may concern:

Be it known that I, EMIL STRANSKY, a citizen of the United States, residing at Canal Dover, in the county of Tuscarawas and State of Ohio, have invented new and useful Improvements in Stands for Electric Irons, of which the following is a specification.

This invention relates to an improvement 10 in stands for electric irons, in the use of which the heat of the iron will be automatically controlled while on the stand.

Electric irons are ordinarily subject to an overheating incident to the continuance of 15 the current to the iron while the iron is not in use, and if the current is cut off from the iron while it is temporarily out of use, a loss of time is incurred in reheating the iron.

The improved stand is designed as a support 20 for the iron and constructed to automatically control the current to the iron, so that the iron, while on the stand, may be practically held at a predetermined heat. The stand is constructed to automatically 25 cut off the current to the iron in the event the iron should become heated to a degree higher than that desired, and following such current cut off, to restore the current to the iron as the temperature of the latter falls 30 below the predetermined degree. The improved construction also contemplates the provision of means for the adjustment of the predetermined heat degree control of the stand, so that in use the iron may be 35 practically maintained at any desired degree of heat.

In the accompanying drawings:—

Figure 1 is a bottom plan of the preferred 40 form of the improved electric iron stand, the bottom plate being removed,

Fig. 2 is a section on the line 2—2 of Fig. 1,

Fig. 3 is a section on the line 3—3 of Fig. 1,

Fig. 4 is a bottom plan view of a slightly 45 modified construction, the bottom plate being removed, and the parts in normal positions.

Fig. 5 is a perspective detail with the contact members used in both forms,

Fig. 6 is a section on the line 6—6 of Fig. 4.

The improved stand, as shown more particularly in Fig. 1 comprises a body 1 of 55 substantially an outline form corresponding to that of the usual electric iron. The body

has a cover plate 2, on which the iron is to rest, and an edge flange 3 preventing accidental displacement of the iron.

Arranged within the stand is a contact 60 member pivotally supported at 4, and insulated from the body, such contact member comprising a contact strip 5, provided adjacent its free end with a contact point 6. The contact member also comprises a second 65 contact strip 7, secured to and insulated from the contact strip 5, adjacent the pivotal connection 4. The free end of the strip 7 is made up of spring sections 8 and 9, the section 8 of which is arranged to contact 70 with the point 6 when the circuit is complete.

The end of the strip 5 is connected to an adjusting member 9, in the form of an L-shaped section, the upright portion of 75 which has a rod 10 projecting through and insulated from the side wall of the stand, and terminally provided with an adjusting nut 11, whereby the contact member as a whole may be adjusted about the pivot 4, 80 and through said nut 11 secured in such adjusted position. This provides for a variation in the heat-control limit of the stand, as will later appear.

Circuit connecting wires 12 and 13, terminally connected to the usual plug 14, lead through one wall of the stand, the wire 12 being connected to one contact strip as 7, and the wire 13 to one terminal 15 of a push plug socket 16 opening through one side 90 wall of the stand. The other terminal 17 of the push plug socket is connected by a conductor 18 through the other contact strip 5. A condenser 19 is connected across the circuit for the usual purpose. The push 95 plug socket 16 is designed to receive the terminals 17' of the circuit wires leading to the electric iron, so that said iron is at all times heated through the stand.

Secured to the underside of the cover 100 plate 2 is the thermostatic control element, whereby the circuit connections are cut in and out to automatically control the heat degree of the iron while on the stand. This thermostatic element comprises two metallic 105 strips of widely different coefficient of expansion under heat, such strips being connected together at the respective ends, and the element as a whole connected to the cover plate, as at 20. These strips 21—22, 110 while connected together at the end remote from the cover plate connection 20, are free

from said cover plate at such end, and are here provided with a lateral lug 23, said lug being arranged to extend through a notch 24 in member 5 to engage the strip 7.

In this form of the device, with the electric iron on the stand the heat of the iron will be communicated to the cover plate, and thereby effect the thermostatic element. As such heat reaches the predetermined point the strips of the thermostatic element cause a reflex action thereof to an extent to move the lug 23 into contact with the strip 7 and raise the spring section 8 thereof from the contact point 8'. The circuit to the iron is thus interrupted and the iron cools to the predetermined heat point, at which heat degree the thermostatic element has again permitted the contact strips 5 and 7 to close the circuit.

In Figs. 4 and 6 is illustrated a slightly modified construction in which the contact strips, here indicated as 5' and 7', while substantially identical in construction with the previously described strips 5 and 7 are fixed 25 upon an insulating block and are not adapted for adjustment.

In this form the thermostatic element, herein indicated as 25, is seated within a depression 26 in the underside of the cover plate, in order that the thickness of said plate between the surface of the electric iron and the thermostatic element may be so thin that the heat of the electric iron will be readily communicated to the thermostatic element. In the latter form of stand the thermostatic element is shown as provided with an upstanding rod 27 to underlie the contact strip 7, for the operation of such contacts in cutting in and out the circuit.

The arrangement of the thermostatic element within the depression 26 of the cover plate 2 may, of course, be applied to the form illustrated in Figs. 1 to 4, or said thermostatic element may be otherwise disposed if desired so long as it may be readily affected by the heat from the electric iron.

In the forms shown in Figs. 1 to 4 the adjustment of the contacts about the pivot 4, will, of course, adjust the contact strip 7 relative to the lug 23 of the thermostatic element, and through this adjustment the degree of heat necessary to move the thermostatic element to open and close the circuit may be varied at will.

While the iron is in use the contact strips 5 and 7 are closed and the heating circuit to the iron passes through the stand without any effect on the control elements of the stand. When it is desired, however, that the iron shall be held at practically a predetermined heat, no matter how long it may be out of use, the electric iron is placed on the stand, and the latter automatically controls the heat as described.

The improved construction provides an

electric iron stand by which the temperature of the iron while on the stand is automatically controlled to prevent overheating of the iron without permitting the iron to cool off to an undesirable extent. Furthermore, 70 the improved stand is readily adapted for use with any type of electric iron; if designed for household or commercial use with any type of electric connection, and may be connected and disconnected as 75 readily and conveniently as the usual iron.

Of course, it is to be understood that the cover plate 2 is preferably made of a metal which will readily and quickly radiate the communicated heat, in order that when the 80 iron is lifted from the stand for use the thermostatic element may be quickly cooled, in order to maintain the electric connection to the iron.

Having thus described the invention, 85 what I claim is:

1. A stand for electric irons including a cover plate, contact strips controlling the circuit through the stand to the iron, and a thermostatic element carried by and in direct contact with the cover plate to actuate said contact strips.

2. A stand for electric irons including a cover plate on which the iron is to rest, contact strips controlling the circuit through 95 the stand to the iron, a thermostatic element secured to and in direct contact with the cover plate, and a lug on said element to engage one of the contact strips in the movement of the element under the action of 100 heat.

3. A stand for electric irons including a body having a cover plate, a thermostatic element secured to and carried by said cover plate, contact strips arranged in the circuit 105 leading through the stand to the iron, one of said strips being of spring type, and means carried by the thermostatic element to engage and operate said spring contact strip to control the circuit to the iron.

4. A stand for electric irons including a body having a cover plate, a push plug socket arranged in the body to receive the electric iron conductors, contact strips arranged in the body, one of said strips being 115 connected to one terminal of the push plug socket, conductor wires leading to the stand and connected respectively to one contact strip and the remaining push plug socket terminal, and a thermostatic element secured to the cover plate and adapted to operate contact strips under a predetermined heat.

5. A stand for electric irons comprising a body having a cover plate, contact strips 125 arranged in the body and controlling an electric circuit leading through the stand and to the iron, a thermostatic element carried by the cover plate and adapted to control the contact strips, and means for ad- 130

justing the contact strips to vary the control of the thermostatic element.

6. A stand for electric irons comprising a body having a cover plate, a contact member mounted for pivotal movement in said plate and comprising relatively insulated contact strips for controlling the circuit leading through the stand to the iron, a thermostatic member carried by the cover plate and adapted to control one of said strips, and means for moving the contact member about its pivotal support.
7. A stand for electric irons comprising a

body having a cover plate, a contact member mounted for pivotal movement in said plate and comprising relatively insulated contact strips for controlling the circuit leading through the stand to the iron, a thermostatic member carried by the cover plate and adapted to control one of said strips, means for moving the contact member about its pivotal support, and means for securing the contact member in adjusted position.

In testimony whereof I affix my signature. 25
EMIL STRANSKY.
